WAR PROTECTING DEVICE

Souren Kazanjian, Woodside, N. Y.

Application May 8, 1936, Serial No. 78,579

4 Claims. (Cl. 89—36)

This invention relates to new and useful improvements in a war protecting device.

The invention has for an object the provision of a substantially horizontal wheel to act as a shield and adapted to be rotated to centrifugally throw bombs and other explosives dropped on articles and devices being protected. For example, several of the protecting devices may be mounted upon a ship and protect the ship from aerial bombs.

Still further the invention contemplates the provision of a spiral hub upon the wheel device arranged in a manner so as to be capable of quickly dispersing poisonous gases.

Still further the invention proposes the adaptation of the war protecting device to underground forts and other strategic positions.

Still further the invention proposes the provision of a revolvable closure element in the top of a chamber or underground passage and having a small entrance door associated in a novel manner with a stationary member extending over one side thereof and having a door alignable with said door.

Furthermore, the invention contemplates the association of a substantially horizontal wheel acting as a shield and superimposed on said closure.

For further comprehension of the invention and of the objects and advantages thereof, reference will be had to the following description and accompanying drawings, and to the appended claims in which the various novel features of the invention are more particularly set forth.

In the accompanying drawings forming a material part of this disclosure:—

Fig. 1 is a side elevational view of a ship equipped with several war protecting devices according to this invention.

Fig. 2 is a plan view of Fig. 1.

Fig. 3 is a perspective view of one of the war protecting devices involving a modification of the invention.

Fig. 4 is a vertical sectional view of Fig. 3.

Fig. 5 is a fragmentary enlarged detailed view of a portion of Fig. 4.

Fig. 6 is a transverse sectional view taken on the line 6—6 of Fig. 5.

Fig. 7 is a fragmentary enlarged sectional view taken on the line 7—7 of Fig. 6.

Fig. 8 is a fragmentary enlarged detailed view of a portion of Fig. 4.

In Fig. 1 a ship 10 is shown provided with several war protecting devices 11. Each of these devices includes a substantially horizontal wheel 11^a acting as a shield. Means are associated with the wheel for turning the wheel to centrifugally throw bombs and other explosives dropped thereon.

The wheel 11^a comprises a rim portion sup-

ported by a plurality of adjacent fan shaped spokes 12 which in turn are connected with a hub portion 13. This hub portion comprises a spiral section 13^a and a plurality of radial reinforcement members 13^b. A vertical shaft 14 connects with the hub portion of the wheel and is supported in the vertical portion by a pedestal 15. Several arms 16 hold the wheel 11^a in a horizontal position on the vertical shaft 14 and the wheel 11^a.

In operation the war protecting devices prevent bombs and other explosives from being dropped upon the object or device being protected. The wheels 11^a have a sufficient span so as to substantially cover the entire object being protected. The rotations of the wheels prevent bombs and other explosives which are dropped from reaching the protected object. When they strike the wheels they will be thrown by centrifugal force outwards. Furthermore, the spiral hubs 13 of the wheels and the fan shaped spokes 12 are very efficient in dispersing poisonous gases.

In Figs. 3—8 inclusive a modification of the invention has been disclosed wherein an underground passage or the lower compartment of a ship is protected thereby. More specifically, in this form of the invention there is a substantially horizontal wheel 21 which is supported at its center by a vertical shaft 22. This vertical shaft extends downwards through a revolvable closure member 23. This closure member is arranged in the top of the underground compartment or passage 24. A stationary member 25 extends over one side of the revolvable closure element 23 and is attached to a stationary object such as the ground 26.

The wheel 21 has a plurality of fan shaped spokes 27 by which it is connected to a spiral hub portion 28. The vertical shaft 22 is supported by a standard construction 29 which is mounted on the stationary member 25. The revolvable closure element 23 has several rollers 30 mounted on its bottom which ride upon a supporting shoulder 31 built into the ground. This revolvable member 23 is also arranged coaxial upon the shaft 22 and is supported by a flange 32. At the bottom the shaft 22 is provided with a gear 33 which meshes with a pinion 34 of a driving mechanism 35. This driving mechanism is mounted on the floor of the compartment or passage 24.

A plurality of supporting brace arms 36 are mounted in the ground and extend upwards. At their top ends these support arms 36 are provided with rollers 37 rotatable in spring bearings 37'. The rollers are engaged by circular flanges 38 on the periphery of the ring 27.

The extension ring 21^a is spaced by washers 21' from wheel 21 and is concentric with the 60

latter. Rivets 21^b secure members 21, 21' and 21^a together.

Auxiliary arms 39 are movably attached by hinges 39^a at their top ends with the periphery 5 of the ring 21^a. An expansion device 39^b in the form of a turn buckle construction is connected between each of the auxiliary arms 39 and the ring 21^a to hold the arms in various predetermined fixed angular positions. At the lower ends 10 the arms 39 connect with segments 39^c, which when taken together as a unit form an annular member encircling the arms 36. This annular member forms a rotating or moving obstruction to an attacking enemy.

15 The stationary member 25 is provided with a door 40 which is alignable with a door 41 mounted in a small entrance opening in the closure element 23. This door 41 is pivotally supported by a pintle 42 and has a lock 43. This lock has a 20 bolt 44 extending from both ends. The end 44^a is adapted to engage in keeper 45 which holds the door 41 locked. The end 44^b extends into a recess 46 in the door and engages a control slide 47. This control slide is resiliently urged upwards by a spring 48. It is formed with an opening 49 which when aligned with the rear end 44^b of the bolt permits the lock to be opened. The upper end of the slide plate 47 is provided with several teeth 49' adapted to mesh with complementary key teeth 49^a on the material of the stationary member 25 adjacent the door 40. The upper end of the plate 47 slightly projects above the top face of the element 23. The stationary member 25 has a recessed portion 25^a through 35 which the upper end portions 49' of the plate 47 may pass when the element 23 turns. A removable ladder 50 is provided for climbing up through the doors when they are aligned.

40 The operation of the device is as follows:—The driving element 35 rotates the shaft 22 which in turn rotates the closure element 23 and the wheel 21^a which are mounted on the shaft 22. When the device is thus operating an enemy cannot drop bombs or other missiles upon the closure 45 element 23, and furthermore, enemies on the ground cannot gain entrance through the device because of the rotating closure element 23. If they jump on this rotating element with the view of prying the door 41 open they will be hurt by 50 being forced against the stationary element 25. If they open the door 40 of the stationary element 25 they cannot gain access through the door 41, and so cannot enter the underground passage.

55 In order to open the door 41 it is necessary that the driving device 35 be brought to a stop at a position in which the doors 40 and 41 are aligned. In this position, and only in this position, do the key teeth 49^a mesh with the teeth 49' to press 60 down the plate 47 against the action of the spring 48. Then the bolt 44 may be moved towards the left so that it disengages the keeper 45. The door 41 may now swing open.

65 The revolvable closure arrangement illustrated in Figs. 3 to 5 may also be used on ships, on top of forts, buildings, etc.

70 While I have illustrated and described the preferred embodiments of my invention, it is to be understood that I do not limit myself to the precise constructions herein disclosed and the right is reserved to all changes and modifications coming within the scope of the invention as defined in the appended claims.

75 Having thus described my invention what I

claim as new, and desire to secure by United States Letters Patent is:

1. A war protecting device, comprising walls forming a chamber, a revolvable closure element in the top thereof and having a small entrance 5 door, a substantially horizontal wheel for acting as a shield and superimposed on said closure, means for rotating said closure and wheel, a stationary member extending over one side of said closure and having a second door alignable 10 with said entrance door, said entrance door being held closed by a lock having a bolt engaging a keeper adjacent the door, said bolt also engaging against a plate having an opening when aligned with the bolt to permit opening of the 15 bolt, a resilient element urging said plate out of the aligned position, and a key element on said stationary member adapted in a certain pre-determined position of said closure element to urge said plate into the aligned position. 20

2. A war protecting device, comprising walls forming a chamber, a removable closure element in the top thereof, a small entrance door in said closure element, a substantially horizontal wheel for acting as a shield and superimposed on said 25 closure, a means for rotating said closure and wheel, a stationary member extending over one side of said closure, a door in said stationary member alignable with said entrance door, and latch means for said first mentioned door, a second means for locking said latch means and for releasing said latch means when said doors are 30 alignable.

3. A war protecting device, comprising walls forming a chamber, a removable closure element 35 in the top thereof, a small entrance door in said closure element, a substantially horizontal wheel for acting as a shield and superimposed on said closure, a means for rotating said closure and wheel, a stationary member extending over one 40 side of said closure, a door in said stationary member alignable with said entrance door, and latch means for said first mentioned door, a second means for locking said latch means and for releasing said latch means when said doors are 45 alignable, said means for latching said door comprising a bolt on said door, a keeper adjacent said door and engaged by said bolt to hold said door closed.

4. A war protecting device, comprising walls 50 forming a chamber, a removable closure element in the top thereof, a small entrance door in said closure element, a substantially horizontal wheel for acting as a shield and superimposed on said closure, a means for rotating said closure and 55 wheel, a stationary member extending over one side of said closure, a door in said stationary member alignable with said entrance door, and latch means for said first mentioned door, a second means for locking said latch means and for 60 releasing said latch means when said doors are alignable, said means for latching said door comprising a bolt on said door, a keeper adjacent said door and engaged by said bolt to hold said door closed, said means for locking and for releasing 65 said latch means comprising a plate having an opening engageable by said bolt when aligned with said bolt to permit releasing of said bolt, a resilient element urging said plate out of position, and a key element on said stationary member adapted in a certain pre-determined position to said bolt to engage said opening in order 70 to open said doors. 70
